(No Model.)

H. L. BLODGETT.

FASTENER FOR THE MEETING RAILS OF SASHES.

No. 277,980.

Patented May 22, 1883.

UNITED STATES PATENT OFFICE.

HENRY L. BLODGETT, OF CHICAGO, ILLINOIS.

FASTENER FOR THE MEETING-RAILS OF SASHES.

SPECIFICATION forming part of Letters Patent No. 277,980, dated May 22, 1883.

Application filed January 18, 1883. (No model.)

To all whom it may concern:

Be it known that I, HENRY L. BLODGETT, of Chicago, in the county of Cook and State of Illinois, have invented certain new and useful 5 Improvements in Window-Fastenings; and I do hereby declare that the following is a full, clear, and exact description thereof, reference being had to the accompanying drawings, and to the letters of reference marked thereon, 10 which form a part of this specification.

This invention relates to locking devices for windows, of the class more especially intended to be applied to the meeting-rails of the sashes.

Its object is to provide a cheap, simple, 15 easily-operated, and efficient locking device; and it consists in the matters hereinafter described, and pointed out in the claims.

In the accompanying drawings, Figure 1 is a perspective view of a fastening constructed 20 as proposed by my invention. Fig. 2 is a plan view of the same. Fig. 3 is a detail of the end of the locking-lever. Fig. 4 is a fragmentary section on line $\alpha\alpha$ of Fig. 2. Fig. 5 is a plan view of a modified form of the device shown 25 in Figs. 1 and 2. Fig. 6 is an elevation of the stud, and a sectional view of the end of the locking-lever shown in Fig. 5. Fig. 7 is a perspective view of the stud and its supporting-plate shown in Fig. 5. Fig. 8 is a modified form of the stud and plate shown in 30 Fig. 5.

A and B are portions of the upper and lower sash, respectively, of a window as ordinarily constructed, and A' and B' the meeting-rails of the two sashes. 35

C is a bent lever, which is pivoted upon the upper or horizontal surface of the meeting-rail B' of the lowersash by means of a stud or screw, c. The lever C consists of two arms, 40 C' and C², which are preferably placed at right angles to each other, and intersect at or near the pivotal point of said lever. Upon the extremity of the arm C', which is arranged longitudinally in reference to the rail B', is a knob or handle, c', by which said arm may be grasped in operating the lever. The arm C² terminates at or near the face of the vertical side piece, A², of the upper sash, and has an upturned end, c², constructed to engage a 45 screw-stud, D, on the said sash in the manner hereinafter described. The lever C is prefera-

bly constructed of spring sheet metal, and is supported a short distance above the upper surface of the rail B' by means of a plate, E, through one end of which the pivot-screw c 55 passes, and which will be hereinafter more fully described. The end of the arm C² projects beyond the plate E, so that it is unsupported from beneath, and is capable of slight vertical movement on account of the flexibility of the sheet metal of which the lever C is composed, and said arm has an upturned end, c², which is provided with an incline, c³, and a semicircular notch, c⁴, constructed to engage the stud D. The end c² and the notch c⁴ 60 therein are shown more plainly in Fig. 3, which is a sectional view of said end. The notch c⁴ is brought into engagement with the stud D by a lateral movement of the end of the arm C², given to it by moving the end of the arm 65 C'. In this operation the end of the arm C' is forced downwardly by the contact of the incline c³ with the stud until the said stud has passed over the incline and into the said notch. By making the arm C² flexible, as described, and forming the incline c³ on the upturned end thereof, a slight variation in the relative positions of the upper and lower sashes will not affect the operation of the device; but the yielding of the said arm downward will allow it to engage the stud, notwithstanding such variation. The said spring-arm C² also tends to force the upper and lower sash in opposite directions by its upward pressure on the stud when the device is locked, 75 and thus tends to keep the window tightly closed. The downward movement of the arm C² is limited by the upper surface of the rail B' beneath it, so that if an attempt is made to raise the sash said spring will yield slightly 80 until it strikes said rail, and a positive lock will then be formed by the contact of said arm therewith. The end of the lever C² is disengaged from the stud D by drawing the end of the arm C' outward, the notch c⁴ becoming 85 disengaged by the yielding of the end of the arm C², as before described.

The stud D is preferably provided with an enlarged head, d, and the upturned end c² of the arm C² is inclined, as shown in Fig. 2, so 90 that the head d will come in contact with the inclined face of the upturned end, in the oper-

ation of locking, and draw the meeting-rails A' and B' together for the purpose of making a tight joint between said meeting-rails.

One of the locking devices described is preferably placed on each side of the window, so that when it is locked the meeting-rails will be drawn together equally at both ends and a tight joint made between them throughout their entire length. The plate E, upon which the lever C is mounted, extends from the pivotal point of said lever longitudinally beneath and to the end of the arm C', and has a curved projection, E', corresponding with the circular path of the end of said arm. Upon the under side of the arm C' is a short downwardly-projecting pin, c⁵, preferably placed beneath the knob c', and in the plate E', at the two extremities of the movement of said arm, are formed depressions e e, adapted to receive said pin for the purpose of locking the arm C' at either limit of its movement. The pin c⁵ is of such length that it remains normally in the depression e', but may be removed therefrom by raising the end of the arm C', which is sufficiently flexible for this purpose. The end of the arm C' is, by the device described, prevented from being moved accidentally when the fastening is unlocked, and additional security is given to the fastening thereby when locked, the lever C being held in position both by the pin c⁵ in the depression e and by the engagement of the notch c⁴ with the stud D.

In Figs. 1 and 2 the stud D is shown as projecting from the face of the vertical side piece or rail, A², of the upper sash, and in order to allow said stud to pass the projecting edge of the meeting-rail B' when the sashes are moved a notch, b², is made in the said edge, beneath the said stud, as shown in the figures mentioned.

In Figs. 4, 5, 6, and 7 are shown a modification of the device described, in which the stud D is placed in a recess in the piece A², so that the head of the said stud is flush with the face of the said piece, and the notch b² in the rail B² is rendered unnecessary. I have preferably made the stud D in the form of a projection or lug upon a plate, F, which is placed in a recess formed in the corner of the piece A², and secured therein by screws, or in any other desired manner. Such plate and the projection D thereon are shown more plainly in Figs. 6 and 7. A projecting rim, d', corresponding with the head d of the stud D, as shown in the figures last mentioned, is provided for the purpose of acting, in connection with the inclined end of the arm C², to draw the lower portions of the sashes together. When the stud D is placed in a recess, as above described, the end of the lever C² is arranged to project beyond the inner edge of the rail B' when the device is locked, in order to enter said recess, as shown in Fig. 5, and said lever C² is given sufficient movement so that when disengaged from the stud D its ends will not project beyond the rear edge of the rail B', as shown by dotted

lines, which indicate the changed position of the lever C in said figure. It is not essential that the lever C should be bent as shown, but it may be straight, the plate E' in such case being placed in the same position relative to the arm C', as has been before described in connection with the bent lever shown.

In Fig. 8 is shown a modified form of the plate F and stud D, in which the said plate is secured to the upper sash by a screw, (indicated in the figure mentioned by d'), which is provided with a thimble, d', between its head and the plate F, in order to hold said plate in position. Instead of using the thimble d' upon the screw d', as shown, the screw may have an enlarged portion adjacent to its head, which will form a shoulder to press upon the plate F and retain it in position on the sash.

The stud D, instead of being attached to the vertical side piece of the upper sash, as shown, may be placed upon or form part of a standard or bracket attached to the top of the meeting-rail A' of said sash, and in such case said standard or bracket, with the stud thereon, and the pivoted lever C can be placed at the center of the meeting-rails, thus forming a single central fastening, which can be used instead of a locking device at each side of the window.

One or more additional studs, D', as shown in Fig. 1, may be placed upon the upper sash, each of which is arranged to engage the lever C in the manner before described, so that the sashes may be locked together in any one of the several positions. When constructed to lock in several positions the stud D is preferably placed in a recess in the upper sash, and the plate F, which has been described as being used in connection with said stud, is provided with a lower flange, F², as shown in Fig. 8, which acts against the lower side of the end of the arm C², and, in connection with the stud, prevents any movement of the upper sash in either direction when they are locked together in the manner described.

The notch c⁴ in the end of the spring-arm C² is not essential to the operation of the device described, and the upturned end of said arm may be provided with a simple incline, which will rest against the under side of the stud D when the device is locked, the said arm in such case being held in position by the engagement of the pin c⁵ on the arm C' with the depression e in the plate E. When the notch is omitted the inclined edge of the upturned end of the arm C² will act, in conjunction with the flexibility of said arm, both to allow for variation in the position of the stud in closing the window and to press the sashes in opposite directions, so as to tend to close them tightly, as before described.

I claim as my invention—

1. In a sash-fastening, the combination, with a stud affixed to the vertical rail of the upper sash, of a pivoted lever supported upon and above the upper surface of the lower sash, and having an elastic vertically-yielding arm, pro-

vided with an upturned flange upon its free end for engagement with the stud, substantially as described.

2. In a window-sash fastening, the combination of a headed or flanged stud affixed to a vertical rail of the upper sash and a spring-lever pivoted to the upper face of the lower sash, and provided with an upturned flange at its free end for engagement with the stud, 10 said flange being in a vertical plane inclined to the radius drawn through the same from the center of the pivotal movement of the lever, and also inclined on its upper surface, substantially as described, and for the purposes 15 set forth.

3. In a sash-fastening of the character described, the combination, with the flanged stud affixed to the upper sash, of the pivoted spring-lever provided with an upturned and inclined 20 flange at its end for engagement with the stud, said flange being beveled and notched on its upper surface, substantially as described.

4. In a sash-fastener of the character described, the combination, with the spring-lever

C, pivoted between its ends, constructed to engage the stud on the upper sash by one of its arms, as set forth, and provided with a pin, c⁵, on the opposite arm, of a plate, E, supporting the lever at its pivotal point, whereby the stud-engaging arm may be depressed, and provided with one or more notches or depressions, e', to admit the end of the pin c', substantially as described.

5. In a fastening device for windows, the combination, with an upper and a lower sash, 35 of a recessed plate, F, upon the upper sash and a pivoted spring-lever secured to the lower sash, and constructed and arranged to engage in said recess, substantially as and for the purposes set forth.

In testimony that I claim the foregoing as my invention I affix my signature in presence of two witnesses.

HENRY L. BLODGETT.
